UNITED STATES PATENT OFFICE.

WILLIAM L. MORRIS, OF CLEVELAND, OHIO, ASSIGNOR TO THE AUSTIN
CARTRIDGE COMPANY, OF SAME PLACE

WAD-FEEDING DEVICE.

SPECIFICATION forming part of Letters Patent No. 678,827, dated July 16, 1901.

Application filed March 20, 1899. Renewed June 24, 1901. Serial No. 65,881. (No model.)

To all whom it may concern:

Be it known that I, WILLIAM L. MORRIS, a citizen of the United States, and a resident of Cleveland, county of Cuyahoga, and State of Ohio, have invented a new and useful Improvement in Wad-Feeding Devices, of which the following is a specification, the principle of the invention being herein explained and the best mode in which I have contemplated applying that principle so as to distinguish it from other inventions.

My invention relates to that class of machines designed to feed cut wads into shell-loading machines, and particularly to improvements in the wad-feeding device shown and described in my application for United States Letters Patent, Serial No. 705,363, filed February 13, 1899.

The general construction of my improved device is similar to that shown in the above-named application, the principal changes being directed, first, to the wad-holder, the improved form of which permits the use of smooth-faced instead of the undulate cams and results in a smooth reciprocating and angular movement on the part of the wad-holder, an advantageous feature in large machines, and, second, to the wad-spout and means for removing the wad-holder.

The annexed drawings and the following description set forth in detail certain mechanism embodying the invention, such disclosed means constituting but one of various mechanical forms in which the principle of the invention may be used.

In said annexed drawings, Figure I represents a side elevation of my improved wad-feeding device. Fig. II represents a partial central transverse section taken upon line 22, Fig. I, and showing the upper portion of the wad-carrier and attached wad-holder in elevation. Fig. III represents a perspective and enlarged view of the end of the wad-holder and the removable spout seated in a broken portion of the wad-hopper side. Fig. IV represents a perspective of the wad-spout seated in a broken portion of the hopper side as viewed from the side opposite that from which the view shown in Fig. III is taken. Fig. V represents an enlarged cross-section of the

wad-holder with wads therein; and Fig. VI represents a vertical longitudinal section of the entire machine, showing certain parts in the sectional plane in elevation.

In order that the operation of my specific improvement may be fully understood, I shall first describe briefly the general operation of the whole machine.

A wad-hopper A, mounted upon a frame B and having downwardly-converging sides, has slidably mounted in it a vertically-reciprocable plate C, upon the upper edge of which is hinged a movable wad-holder D, formed with a wad-race d. A lifter E, vertically reciprocable, engages the under surface of the wad-holder. The lower ends of plate C and lifter E are each provided with a roller E' and C², respectively. Two rotatable cams F and G, driven by suitable shafting H and J, gearing J' and J², and a driving-pulley J², respectively engage and oscillate two levers K and L, whose ends engage the rollers E' and C², respectively, as shown. The two cams are so constructed and placed relatively to each other that upon their rotation the plate C and lifter E will be simultaneously raised until the plate reaches the upper extremity of its stroke, from which point, however, the lifter is further raised, so as to tilt the wad-holder upon its pivotal center, as shown in Fig. II in dotted lines. The cams continuing their rotation, the reverse of the above operation takes place, plate, lifter, and wad-holder reassuming their original positions.

The wad-holder D is provided with the wad-race d, the upper surface of whose respective sides are of undulate formation, the undulations of the one side alternating with those of the opposite side of the race. At the point in the hopper-wall contiguous to the hinged end of the wad-holder when the plate C is at the upper extremity of its reciprocal stroke is formed a discharge-opening A', Fig. II. The end of the holder contiguous to the wad-spout or discharge-opening A' is provided with a hood D', which overhangs the wad-race and is of a height such that a wad may pass over a wad below in the race. The inner surface of said hood is inclined or curved, so as to deflect wads laterally therefrom. Such inclined

surface is continued in a surface *a*, formed contiguous to said discharge-opening, as shown in Fig. IV. These two surfaces form a continuous surface which deflects wads 5 passing above the discharge-opening and causes them to fall back into the hopper *A* without clogging the end of the wad-race and said opening during the discharge of the wads from the holder. The portion of the hopper side containing the discharge-opening is made removable, so that different-sized openings may be used to accommodate different sizes of wads.

The wad-holder being raised as described, 15 the wad-race is filled with wads in various positions, as shown in Fig. V. On reaching its uppermost position the lifter *E* imparts the angular movement to the holder, and the wads start toward the discharge-opening. 20 Those resting entirely in the race pass down freely, while those lying angularly, as shown in Fig. V, encounter the undulations in the sides and are given an upright position, whereupon they are in position to drop into the race 25 when an opportunity is afforded by an interval between two wads already located therein. The alternate arrangement causes such upright position to be assumed at different points, so that two wads will not interfere and 30 crowd each other off the top of the holder. A larger number of wads are hence caused to enter the race and be discharged than were such alternate arrangement not provided. The feeding speed of my improved device is 35 hence only limited by the speed of the driving-pulley *J*², which may be varied to conform with the requirements of the particular shell-loading machine to which it is applied. The portion of the hopper containing the discharge- 40 opening being removable, the wad-holder may at the uppermost limit of its stroke be removed by first removing said portion and then swinging said holder upon the segments *c* and out of the hopper, as shown in dotted lines in 45 Fig. II, whereupon said holder becomes disengaged from said segments and permits of the substitution of a holder of different size. Such removal is thus accomplished without lifting the plate *C* by hand, so as to bring the 50 holder above the rim of the hopper, which is necessitated in the operation in the feeding device shown and described in my above-named application.

Other modes of applying the principle of 55 my invention may be employed instead of the one explained, change being made as regards the mechanism herein disclosed, provided the means covered by any one of the following claims be employed. I therefore

particularly point out and distinctly claim as my invention—

1. In a wad-feeding device, the combination of a wad-receptacle, a wad-holder movable in an upward direction in said receptacle, and means for imparting angular movement in an upward direction to said holder, the latter provided with a trough-shaped wad-race the top edges of whose side walls are of undulate formation, substantially as set forth. 65

2. In a wad-feeding device, the combination with a wad-receptacle, of a wad-holder angularly movable therein, and provided with a trough-shaped wad-race the upper edges of whose side walls are of undulate formation, substantially as set forth. 70

3. In a wad-feeding device, the combination with a wad-receptacle, of an angularly-movable wad-holder in said receptacle provided with a wad-race having side walls whose upper edges are of undulate formation, the undulations of the one side alternating with respect to those of the other side, substantially as set forth. 75

4. In a wad-feeding device, the combination of a wad-receptacle, a wad-holder in said receptacle, and means for imparting angular movement in an upward direction to said holder, the latter provided with a wad-race having two undulate sides, the undulations of one side alternating with those of the other, substantially as set forth. 85

5. In a wad-feeding device, the combination of a wad-receptacle, a wad-holder in said receptacle provided with a wad-race, means for discharging wads from said holder, and means for deflecting wads from said holder and overhanging said wad-race, substantially as set forth. 95

6. In a wad-feeding device, the combination of a wad-receptacle, a wad-holder in said receptacle provided with a wad-race, means for discharging wads from said holder, and means for deflecting wads laterally from said holder and overhanging the end of said wad-race, substantially as set forth. 100

7. In a wad-feeding device, the combination of a wad-receptacle, a wad-holder in said receptacle provided with a wad-race, means for discharging wads from said holder, and means for deflecting wads laterally from the end of said holder and overhanging the end of said wad-race, substantially as set forth. 105

Signed by me this 17th day of March, 1899.

WILLIAM L. MORRIS.
